UNITED STATES PATENT OFFICE.

LOUIS G. FREEMAN AND BENJAMIN W. FREEMAN, OF CINCINNATI, OHIO, ASSIGNEES
TO LOUIS G. FREEMAN, OF CINCINNATI, OHIO, AND CHARLES F. FREEMAN, OF
ST. LOUIS, MISSOURI, TRUSTEES.

SHOE SHAPER.

Application filed December 9, 1925. Serial No. 74,404.

Our invention relates to the general class of shoe shapers and particularly to shoe shapers for shaping shoe uppers and smoothing the backs and sides.

5 It is the object of our invention to provide improvements in shoe shapers and to conform and modify shoe pressers of the type described in the United States patent to Ruff and Ekins, #1,334,968, to which reference is

10 hereby made, in order to provide machines adapted to accomplish new and useful purposes in shoe shaping. We further provide, in the novel modification of the invention referred to, a plurality of forms and shaping

15 members on a rotatable head which enables the shaping of shoes in a novel and efficient manner.

In our improved mechanism by the provision of a plurality of shaping forms within 20 which heating units are disposed the uppers may remain within the shaping mechanism a more evenly regulated time than with the use of single pressers. This enables operation with accurately controlled temperature and 25 pressure which eliminates the possibility of ruining the fine leather of shoe uppers by too great exposure to heat or pressure in the shaping operation.

We provide a turret or rotatable head 30 adapted to carry a series of complementary shaping forms which move in unison so that to an operator the movement of one unit out of accessible position brings the next unit into operating position, so that the position of 35 the operator in placing shoes on the forms need not be changed, and much labor is saved over that required to feed a plurality of individual pressers having no co-operating relation.

40 It is our object in our improved structure to install the electric control mechanism within easy reach of the operator and to so dispose all the connecting parts that there will be little likelihood of damage being done to 45 the electrical connections inadvertently.

It is further our object to provide a vertical adjustment for the assembled turret which may be readily adjusted to accommodate the height of an operator without any changes 50 being required in either the electrical connections or the shaping mechanism.

The electrical mechanism is preferably pro-

vided with a single rheostat which remains stationary but which is connected by means of push pin sockets to stationary brushes 55 which are in contact with rings through which electrical current passes to the individual heating units in the shaping forms. This construction makes a standard head available for any desired number of shaping units without additional changes in structure. 60

It is a specific object of our invention to provide improved means for shaping shoe uppers on forms comprising rotating elements which apply pressure to shoe uppers mounted 65 on forms with a constant force applied during a complete cycle of rotation of the turret head of the machine. It is also an object to provide the rotating elements with a very effective lock on displacement during the 70 cycle of revolution. Inasmuch as the structure herein described may be used for pressing complete shoes and unassembled portions of shoes we have in the ensuing claims, employed the term "shoe element" to include 75 both classes.

An important object of our invention is the application and regulation of sufficient pressure along the sides of shoe uppers, particularly, which will effect a permanent shape. 80 Farther in our novel shoe forms it is our object to provide a structure which may be selectively heated so that some parts of the form will be hot and some parts unheated or some parts will be heated to a greater degree than 85 others.

The aforementioned objects including other specific improvements in the forms and the means of shaping shoe leather thereon are accomplished by that construction hereinafter 90 described.

Referring to the drawings:

Figure 1 is a side elevation partly in section showing the complete assembly with only one of the pressing heads shown. 95

Figure 2 is a top plan view of the assembly shown in Figure 1 with one of the pressing heads indicated in detail.

Figure 3 is an enlarged side elevation of the arm carrying the pressing strap with the 100 details of construction more clearly shown than in Figure 1.

Figure 4 is a sectional view of the portion of the head consisting of the parts for sup-

plying the rotating heating units with current from the stationary rheostat controlled electrical supply lines.

Figure 5 is a detail elevation of the outer shaping strap showing the preferred arrangement of parts on a tension arm for supporting the strap.

Figure 6 is a side elevation of the preferred type of clamping strap.

10 Figure 7 is a vertical sectional view of the strap shown in Figure 6 as indicated by the lines 7-7.

Figure 8 illustrates in side elevation, a preferred type of shoe form.

15 Figure 9 is a horizontal section of the upper portion of the form shown in Figure 8 as indicated by the lines 9-9.

Figure 10 is a side elevation of a modified form of central rod.

20 Generally indicated at 1 is a split hollow column having an enlarged base (not shown) for resting on the floor in which the sleeve 2 carrying the rotating parts of the machine is mounted. The sleeve 2 is vertically adjustable by means of loosening and tightening the bolts 3 which clamp together the split sides of the column. A peripheral flange 4 extending from the sleeve forms the bearing on which the body 5 of the turret head rotates.

25 We have further provided gibbs 6 which prevent upward movement of the body of the turret head and form a convenient means of adjusting the sleeve to a desired vertical position with the elevation of the turret head. Mounted at the sides of the turret head are the shoe forms 7, a preferred type of which is illustrated and in which electrical heating units 8 are mounted. In the illustration we 30 have shown a turret head with four shaping units mounted thereon but as noted the number of heads mounted is merely a matter of choice and any desired number may be mounted on the turret head in the obvious manner.

35 40 45 We have shown the rods 9 secured to the back part of the shaper forms. These rods are preferably of heat insulated material and they play an important part in controlling the clearance of the shaping means during the intervals of applying the work, and the correct seating of the shaping means during the periods of operation. As indicated we prefer to utilize shaping straps to shape the shoe leathers against the forms, although we 50 55 do not limit ourselves to this construction and any means which presses the back and the sides of the shoe against the forms is well within the range of mechanical equivalency.

50 55 60 In slots 10 extending across narrowed portions formed in the lower outer periphery of the turret heads bolts 11 adjustably mount strap bracket arms 12 with a key 13 in a keyway 14 in the turret head permitting adjustment at a desired position on the machined surface of the turret head on which the arm

is mounted so as to properly locate the shaping mechanism.

At the lower extremity of each of the arms 12 a boss is formed which is bored as indicated to mount the shaft 15 which may be suitably retained in the bored aperture with a set screw 16. The shaft 15 carries a pressure arm 17 which straddles the boss and journals on the shaft. The pressure applying lever 18 is also journaled on the shaft at one side of the arm 17 and held in position by a collar 19 secured on the shaft 15 by a set screw 20. The arms 17 and 18 both being loose on the shaft a hinged bolt 21 secured on the arm 18 with a pivot pin 22, forms a connecting member between them. A compression spring 23 is mounted on the bolt 21 and the end of the bolt opposite the pivoted end, passes through a slot 24 in the arm 17. A collar 25 on the end of the bolt forms a means of adjusting the spring to any desired tension so that the two arms are connected together with a spring cushioned joint. The arm 17 has an extension 25^a which carries a strap indicated at 26 in Figure 5 by means of the strap clamp 27 which retains the end of the strap and is journaled pivotally at the end of the arm 17 on a pin 28. An adjustment bolt 29 bearing against the outer end of the clamp 27 forms an adjustable means of retaining the strap 26^a clamp, and the strap also at a desired angle with relation to the arm 17. As the arm 17 pivots into position with the portion 26^a of the strap extending about the shoe form 7 the adjustment of the bolt 29 controls the position of the strap 26 with relation to the form 7. A compression spring 30 mounted in a depressed portion 31 of the arm 17 bears against the end of the clamp 27 opposite to that engaged by the adjustment bolt 29 and holds the end of the clamp against the bolt 29. The means of mounting the pressure strap is such that the strap first extends to an outer limit with relation to the form and then the spring 30 allows the strap to fit snugly over the work mounted on the form.

100 105 110 115 The arm 12 has an extension illustrated in Figure 3 carrying the hardened arc 32 which is rectangular in section with a machined upper and lower face. A locking bar 33 having a slot 33^a of greater size than a section of the hardened arc is pivotally mounted on the arm 18 by means of a pivot pin 34. The lock bar has disposed in an off center position with relation to the clearance slot 33^a 120 hardened steel friction pins 35 which with the rocking of the lock bar on the pivot pin 34, bear against the hardened arc 32. A releasing lever 36 mounted on a pin 37 in the arm 18 has a bearing lug 38 which with the movement of the lever 36 abuts the side of the lock bar and rocks the lock bar so that the friction pins 35 will clear the arc and allow the arm 18 to be moved to desired position. Excepting during 125 periods of pressure on the releasing lever 36 130 135

the lock bar is pressed toward locking position by a spring 39 extending from a boss 40 on the arm 18 and which preferably extends into an aperture 41 in the lock bar which 5 forms a seat for the end of the spring.

The arm 12 has an extension 42 which is engaged by a spring clip 43 extending from the arm 18 which holds the pressure applying arm in disengaged position while work is being placed on the forms. The operation of the pressure applying arm is, because of the above noted structures, very simple. When it is desired to press the upper of a shoe the shoe is placed on one of the forms. The strap 15 26^a is meanwhile held out of position by the spring clip 43 engaging the extension 42. By pulling down the end of the arm 18 the strap may be tensioned to any desired degree and during the rotation of the turret head the 20 locking bar 33 provides a means of holding whatever pressure has been applied to the pressure strap without slippage. Upon the presser head completing a cycle of rotation the pressure strap is released by pressure on 25 the releasing lever 36 which has a handle 44 disposed within a channel 45 in the arm 18 so that the releasing lever and the end of the arm 18 may be moved simultaneously with the fingers gripping the handle 44 of the releasing lever and the end of the arm 18 with 30 the same movement.

In order to provide a convenient means for halting the rotation of the pressing units conveniently to an operator the sleeve 2 has a 35 series of V-shaped grooves 46, illustrated in Figure 4, into which locating plug 47 mounted in a sleeve 48 in the turret head and compressed inwardly with a spring 49 seats at intervals in the rotation of the head. A click 40 denotes that the locating plug is seated and the operator then places the work on the form. By a slight pressure the locating pin moves up the beveled edges of the groove and another unit revolution may be made by a manual 45 push on the handle at the end of the arm 18.

The heating units 8 are preferably connected with the lead wires 50 covered with insulating beads in a split bushing 51 which retains the connector member 51^a. Retained in the 50 turret head are two rings 52 insulated from each other by fiber discs 52^a to which the lead wires are connected. At the top of the sleeve 2 insulated on a fiber disc 53 the electrical distributing head is disposed. The head has 55 bolts 54 which extend through the head and the nuts 55 on these bolts serve to retain a pedestal base of the rheostat column 56. Fiber washers may be utilized to form a perfectly insulated mounting plate between the distributing head and the base of the rheostat column. In the distributing head electrical contact brushes 57 are connected with lead wire push pin terminals 58 over which the female couplings on the wires from the rheostat 60 may be easily inserted. The electrical

contact brushes are disposed one about the other so that during the rotation of the turret head each brush contacts with one of the rings 52 so that current may be continuously applied from the rings to any number of 70 pressing units. There is no variation in the alignment of the brushes and the rings with vertical adjustment of the sleeve 3 as both the rotating rings and the stationary brushes are mounted on the sleeve 2.

The rheostat, generally indicated at 59, has a control handle 60 for regulating the current which passes to the distributing head through the wires 61. A switch 62 mounted on the column above the rheostat has connecting 80 wires 63 to the rheostat which wires are also connected in series with a red signal light 64 mounted on the outer cover of the rheostat casing. Electric lines 65 which extend through a conduit 66 formed in the side of the 85 column serve to supply the switch with electric current from any convenient source.

The electrical contact parts in the column are carefully insulated from each other with fiber discs and fiber discs are used for mounting plates so that if we use a metallic casing 90 there will be no tendency to short circuit the current and burn out the fuses on the lines.

The preferred type of strap secured to the tension arms is indicated in Figures 6 and 7. 95 The structure consists of the outer strap 26 which is fastened as noted within the clamp plate 27. A contact liner 67 may be suitably secured within the strap 26 with snaps 68 and a snap strap 69 extending from ends 70 of the 100 liner which are extended about the side edges of the strap. Between the inner liner and the outer strap pads 71 which may be suitably made of rubber are riveted or otherwise secured to the outer strap. When tension is 105 applied it will be obvious that not only will downward pressure be attained at the back edge of the shoe band but the pads will press inwardly against the sides of the shoe adjacent the back and by varying the shape of the 110 pads and the shape of the form any desired shape may be obtained on the shoe. Further, in order to open out the strap during the movement upward we preferably provide spring strips 71^a which are tensioned away 115 from each other and open out the straps to provide clearance during periods of applying the work. In the modification shown in Figure 10 we have provided a curved rod which limits the movement of the strap transversely 120 away from the form and with its bent over top 9^a limits the upward movement of the strap and causes it to spread out. This modification is particularly useful when combined with straps which are not provided with the spring 125 strips 71^a.

To the best of our knowledge and belief no one has heretofore shaped a shoe by mounting the shoe on a form and then compressing the shoe with outer members which not only press 130

down on the back but which also press inwardly on the sides of the shoe.

Although we have shown a machine with a plural number of pressing units, it should be understood that the units singly provide a new usefulness in shoe shaping not heretofore known. In the claims which follow we have referred to main pressing means and auxiliary pressing means. We have further referred to means for localizing pressure. When we refer to main pressing means we have in mind the strap assembly or its mechanical equivalent. When we refer to auxiliary pressing means we refer to the pads which press inwardly on the sides of the shoes. We of course include the mechanical equivalents of these structures. To the best of our knowledge and belief no one has provided pressing means for pressing and shaping the portions of shoe elements in our preferred manner. When we refer to "means for localizing pressure" we use this phrase to indicate pressing means which may be provided in almost any predetermined manner to various contours as is made possible by the preferred combination which we have disclosed. By varying the thickness and shape of the pads and changing their location we can bring pressure to bear on selected portions of shoe parts which will be independent of the direct pressure applied by the upper inner surface of the strap assembly. Thus by increasing the thickness of the pads and locating them nearer to the top of the strap we can exert all the downward pressure of the strap assembly on the curved sides of the shoes. Thus no pressure need be applied positively to the back seam of the shoe. It is the adaptability of this preferred assembly for exerting pressure in a desired part of a shoe independent of the back seam pressure which we have referred to in terms of means for localizing pressure.

The preferred type of form is indicated in Figures 7 and 8. The inner lower portion of the form is cored out as indicated at 72 to permit the outer sides of the form to quickly radiate off heat. This structure prolongs the life of the inner liner 67 of the shaping strap which otherwise would be subjected to the heat of the form especially when low shoes were being shaped. Heat insulating material might also be used to accomplish this purpose. The preferred type of shaping strap is as noted mounted on snaps so that the liner 55 may be readily replaced when the liner is burned but as an added precaution we prefer to hollow out the form or otherwise insulate it. Inasmuch as in shaping shoes the sock lining is usually of leather which will not stand much heat without curling we have shown the outer end of the form composed of a fiber plate 73 with an asbestos gasket 74 disposed between the form and the plate 73. Thus the sock lining is not heated to such an extent as the back band and sides of the shoe

which it is our desire to heat particularly. By disposing the heating units 8 at an angle within the forms as indicated in Figure 8 we are further able to control the heat to the desired part of the form, particularly for oxford shoes. The rods 9 which as noted are preferably insulated so as not to burn the straps guide the straps upwardly at an incline when the clamping arm is released so that the strap will readily slip back over the work at the start of the movement of the tensioning arm toward tensioning position. As far as we are aware no one has previously provided a form for shoes in which the temperature of selected portions of the form is controlled, with cored-out apertures, insulated pieces or other means. Modifications will readily occur to those skilled in the art for shaping other portions of a shoe by the utilization of equivalent devices so that we do not wish to limit ourselves to machines for the shaping of shoe backs and sides only.

In our preferred type of shoe shaper it is our desire to provide a standard set of forms for similar runs and for this reason we may provide a form which is best illustrated in the sectional view in Figure 9. The outer edge of the insulated piece indicated at A rests against the bottom of the inner side of the heel portion. The portion B is usually against the sides of the shoe on smaller sizes but not in larger sizes. In all types, however, we find that the important portion of the back and sides to shape is that indicated at C and we find that irrespective of the size, a well formed shoe may be shaped at the heel end, even though the portion B does not always fit snugly against the inner side of the shoe in all sizes.

Having thus described our invention, what we claim as new and desire to secure by Letters Patent, is:

1. A shoe shaper comprising in combination a machine support, a member movable thereon, a plurality of pressing forms mounted on said member and movable therewith, and co-operating outer pressing members adapted to bear against said forms mounted on said movable member and means of compressing selected portions of said outer pressing members over said forms.

2. A shoe shaper comprising in combination a machine support, a member movable thereon, a plurality of pressing forms mounted on said member and movable therewith, and co-operating outer pressing members adapted to bear against said forms mounted on said movable member and means of compressing selected portions of said outer pressing members over said forms, said means comprising handles with means of locking said handles with the outer pressing members in tensioned position.

3. A shoe shaper comprising in combination a machine support, a member movable

- thereon, a plurality of pressing forms mounted on said member and movable therewith, and co-operating outer pressing members adapted to bear against said forms mounted on said movable member and means of compressing selected portions of said outer pressing members over said forms, said means comprising handles with means of frictionally locking said handles with the outer pressing members in tensioned position.
4. A shoe shaper comprising in combination a machine support, a manually movable member thereon, a plurality of pressing forms mounted on said member and movable therewith, and co-operating outer pressing members adapted to bear against said forms adjustably mounted on said movable member and means of compressing selected portions of said outer pressing members over said forms, said means comprising handles with means of locking said handles with the outer pressing members in tensioned position.
5. A shoe shaper comprising in combination a machine support, a manually movable member thereon, a plurality of pressing forms mounted on said member and movable therewith, and co-operating outer pressing members adapted to bear against said forms adjustably mounted on movable member head and means of compressing selected portions of said outer pressing members over said form, said movable member head having temporary locking means for locating each shaping unit in position accessible to an operator.
6. A shoe shaper comprising in combination a support, a member movably mounted thereon, a plurality of shaping forms mounted on said member, outer work shaping means adapted to engage about said forms, and means of heating said forms.
7. A shoe shaper comprising in combination a support, a member movably mounted thereon, a plurality of shaping forms mounted on said member, outer work shaping means adapted to engage about said forms, and means of electrically heating said forms, and electric terminal means mounted on said support and having connections with said heating means in said plurality of shaping forms.
8. A shoe shaper comprising in combination a support, a head rotatable thereon, a plurality of shaping forms mounted on said head, outer work shaping means adapted to engage said forms, and means of electrically heating said forms, a stationary rheostat mounted on said support and said heating means supplied with current therethrough, and a switch for controlling the electric current supplied to said rheostat, with an electric indicating device for indicating current conditions within said heating units, said heating units electrically connected with insulated rings mounted on said head and stationary brushes mounted on said support adapted to wipe said rings.
9. In a shoe shaper, means of shaping shoes comprising movable forms and means movable with said forms adapted to be pressed about said forms, said pressing means provided with means for localizing pressure on selected portions of said forms.
10. In a shoe shaper, a form adapted to fit within a shoe, means to apply localized pressure against said form, means for controlling said first mentioned means, and a frictionally locking member for retaining said last mentioned means in position with the first mentioned means compressed about said form.
11. In a shoe shaper, a form adapted to fit within a shoe, means to apply localized pressure against said form, a member for controlling said pressing means, and means retaining said member in position with said pressing means applied, and adjustable means for regulating the position of said pressing means with relation to said form.
12. In a shoe shaper, a form adapted to fit within a shoe, means to apply localized pressure against said form, a member for controlling said pressing means, and means for retaining said member in position with said pressing means applied, and adjustable means for regulating the position of said pressing means with relation to said form, and means for regulating the disengaged position of said pressing means.
13. In a shoe shaper, a form adapted to fit within a shoe, means to apply pressure against said form, a member for controlling said pressing means, and means for retaining said member in position with said pressing means applied, and adjustable means for regulating the position of said pressing means with relation to said form, and means for regulating the disengaged position of said pressing means, said last mentioned means comprising an abutment element disposed so as to guide the movement of said pressing means.
14. In a shoe shaper having movable forms with means for shaping shoe uppers disposed on said forms during cycles of movement, heating units for said forms with means for regulating current supplied to said heating units, and electrical connections for said means, comprising stationary brushes and brush engaging means.
15. A shoe shaper having movable forms with means for shaping shoe uppers disposed on said forms during cycles of movement, heating units for said forms with means for regulating current supplied to said heating units, and electrical connections for said means, comprising brushes and brush engaging means, with means of regulating the horizontal position of said movable forms.
16. In a shoe shaper, a supporting column, a vertically slidable sleeve, means of control-

- ling the position of said sleeve with relation to said column, a head manually rotatable on said sleeve, shoe forms mounted on said head, and adjustable pressing means adapted to be compressed about said forms. 5
17. In a shoe shaper, a supporting column, a vertically slideable sleeve, means of controlling the position of said sleeve with relation to said column, a head manually rotatable on said sleeve, shoe forms mounted on said head, and adjustable pressing means adapted to be compressed about said forms, and partially locking means for locating the position of said head. 10
18. In a shoe shaper, a supporting column, a vertically slideable sleeve, means of controlling the position of said sleeve with relation to said column, a head manually rotatable on said sleeve, shoe forms mounted on said head, and adjustable pressing means adapted to be compressed about said forms, and partially locking means for locating the position of said head, said partially locking means comprising spring tensioned lugs and beveled edge apertures in said sleeve. 15
19. In a shoe shaper comprising movable forms with electric heating units therein, centrally located stationary current distributing members with rotatable means wiping said members, said rotatable means connected with said heating units. 20
20. In a shoe shaper comprising movable forms with electric heating units therein, centrally located stationary current distributing members with rotatable means wiping said members, said rotatable means connected with said heating units, and means of controlling the current supplied to said current distributing members. 25
21. In a shoe shaper, a heated form, pressing means for engaging said form provided with auxiliary means of localizing pressure on selected portions of said form, and adjustable means for regulating the position of said pressing means with relation to said form. 30
22. In combination with a shoe shaper, a heated form, pressing means for engaging said form provided with auxiliary means for localizing pressure on selected portions of said form, adjustable means for regulating the position of said pressing means with relation to said form, and means for maintaining said regulated position. 35
23. In a shoe shaper, a form for a shoe, means of heating said form, and means of controlling the dissipation of heat in selected portions of the form, pressing means and an insulated element extended from said form adapted to support said pressing means clear of said form. 40
24. In a shoe shaping machine, the combination of a form adapted to support a shoe element, and pressing means for pressing a shoe element between said form and said
- pressing means, said pressing means comprising means for applying pressure against portions of a shoe element supported on said form, and said pressing means also comprising auxiliary pressing means operable in conjunction with said first named pressing means, for applying pressure against selected portions of a shoe element supported on said form. 70
25. In a shoe shaping machine, the combination of a form adapted to support a shoe element, and pressing means for pressing a shoe element between said form and said pressing means, said pressing means comprising means for applying pressure against portions of a shoe element supported on said form, and said pressing means also comprising auxiliary pressing means operable in conjunction with said first named pressing means, for applying pressure against selected portions of a shoe element supported on said form, and means for maintaining said pressing means in pressing position during a cycle of operation of said machine. 80
26. In a shoe shaping machine, the combination of a form adapted to support a shoe element, and pressing means comprising the combination of members for applying pressure to the back and sides of a shoe element on said form, and means operable simultaneously with and in conjunction with said members for applying increased pressure to selected portions of the sides of said shoe element. 85
27. In a shoe shaper, a form for supporting a shoe element in other than flat position, pressing means for pressing a shoe element supported on said form, said pressing means comprising main pressing means movable with relation to said form in a certain direction, and auxiliary pressing means operatively connected with said main pressing means, said auxiliary pressing means also movable with relation to said form but movable in a different direction than said main pressing means, said auxiliary pressing means carried by said main pressing means. 90
28. In a shoe shaper, a form for supporting a shoe element in other than flat position, pressing means for pressing a shoe element supported on said form, said pressing means comprising main pressing means movable with relation to said form in a certain direction, and auxiliary pressing means operatively connected with said main pressing means, said auxiliary pressing means also movable with relation to said form but movable in a different direction than said main pressing means, and means for heating said form. 105
29. In a shoe shaper, a form for supporting a shoe element in other than flat positions, pressing means for pressing a shoe element supported on said form, said pressing means comprising main pressing means movable with relation to said form in a certain direc- 115
- 120
- 125
- 130

tion, and auxiliary pressing means operatively connected with said main pressing means, said auxiliary pressing means also movable with relation to said form but movable in a different direction than said main pressing means, and means for heating said form, said means being so arranged with relation to said form that certain portions of said form are selectively heated to heat a shoe element mounted thereon in the portions thereof adapted to be pressed by said pressing means.

30. In a shoe shaper, a form for supporting a shoe element in other than flat position, pressing means for pressing a shoe element supported on said form, said pressing means comprising main pressing means movable with relation to said form in a certain direction, and auxiliary pressing means operatively connected with said main pressing means, said auxiliary pressing means also movable with relation to said form but movable in a different direction than said main pressing means, and means for heating said form, said means being so arranged with relation to said form that certain portions of said form are selectively heated to heat a shoe element mounted thereon in the portions thereof adapted to be pressed by said pressing means, and said form having insulated portions so as to avoid excess heating of a shoe element in portions thereof not to be pressed.

31. In a shoe shaper, pressing means and a heated form, said form provided with means for the selective heating thereof in portions in pressing alignment with said pressing means, and selectively insulated portions in said form.

32. In a shoe shaper, pressing means and a heated form, said pressing means comprising main pressing means movable with relation to said form in a certain direction, and auxiliary pressing means co-operative and movable with relation to said form in a different direction with said main pressing means, and said heated form having a heat unit so arranged therein as to heat a shoe element selectively in the portions in pressing alignment with said main and auxiliary pressing means.

33. In a shoe shaper, pressing means and a heated form, said pressing means comprising main pressing means movable with relation to said form in a certain direction, and auxiliary pressing means co-operative and movable with relation to said form in a different direction with said main pressing means, and said heated form having a heat unit so arranged therein as to heat a shoe element selectively in the portions in pressing alignment with said main and auxiliary pressing means, and said form having selectively insulated portions.

34. In a shoe shaper, means having contoured surfaced portions for supporting a

shoe element, and pressing means for localizing pressure against selectively predetermined portions of said first mentioned means, said first and second mentioned means movable one with relation to another, and means for heating said form.

35. In a shoe shaper, means having contoured surfaced portions for supporting a shoe element, and pressing means for localizing pressure against selectively predetermined portions of said first mentioned means, said first and second mentioned means movable one with relation to another, and means for heating said form in the contoured surfaced portions.

36. In a shoe shaper, pressing means and a heated form, said form provided with means for the selective heating thereof in portions in pressing alignment with said pressing means, and selectively insulated portions in said form, for regulating the shrinkage of portions of a shoe element disposed on said heated form.

37. In a shoe shaper, pressing means and a heated form, said form provided with means for the selective heating thereof in portions in pressing alignment with said pressing means, and selectively insulated portions in said form, the selectively heated portions providing heat for shrinking portions of a shoe element disposed on said form, and the selectively insulated portions preventing the shrinkage of other portions of a shoe element.

38. In a shoe shaper, a form for a shoe, means for heating said form, and means for relatively inhibiting the heating of selected portions of said form, said portions comprising those which on the form lie adjacent the sock lining of a shoe disposed on said form.

39. In a shoe shaping machine, a form for introduction into the back of a shoe over which said shoe is to be shaped, said form having insulated portions adjacent the sock lining, means for heating said form, and means for applying external localized pressure about said form, comprising a member adapted to conform to the shape of the form.

40. In a shoe shaping machine, the combination of a form adapted to support a shoe element, and pressing means comprising the combination of members for applying pressure to the back and sides of a shoe element on said form, and means operable in conjunction with said members for applying increased pressure to selected portions of the sides of said shoe element, and means for heating said form.

41. In a shoe shaper, means of shaping shoes comprising a form, and means adapted to be pressed about said form, said pressing means provided with means for localizing pressure against selected portions of said form, and means for heating said form.

42. A machine for shaping shoes comprising a plurality of shaping forms, a rotatable carriage on which said forms are mounted, heating units associated with said forms, and means for distributing current to said heating units.
43. A shoe shaper comprising in combination, a support, a member movably mounted thereon, a plurality of shaping forms mounted on said member, and means for heating said forms, said shaping forms provided with means for causing the engagement of the linings of a shoe upper with said forms.
44. A shoe shaper comprising in combination, a support, a member movably mounted thereon, a plurality of shaping forms mounted on said member, and means for heating said forms, said shaping forms provided with means for causing the engagement of the linings of a shoe upper with said forms.
45. A shoe shaper comprising in combination, a machine support, a member movable thereon, a plurality of forms mounted on said member and movable therewith, means for causing the engagement of the linings of shoe uppers with said forms, and means for retaining said means in engaged position.
